WALTER D. STOCKLY, OF PITTSBURGH, PENNSYLVANIA, AND EVERETT DRENNEN, OF BRONXVILLE, NEW YORK.

CONVEYING SYSTEM.

Application filed November 14, 1925. Serial No. 69,056.

The present invention relates broadly to material handling apparatus, and more particularly to apparatus of this character in the form of conveyors adapted for the handling and removing of coal and the like from mines, although the utility of the invention is not limited with respect to the particular use to which it is put or the material being handled.

10 A conveyor system for mining, or for other operations in which the loading point moves relatively to the discharging point, must be capable of being lengthened or shortened from time to time as the loading point recedes from or approaches the discharge point. At still greater time intervals the entire system must be capable of removal bodily to other positions, or a new locus of operations. Extendible and movable conveyor systems have 15 heretofore been proposed, but they have been objectionable or deficient either with respect to portability or with respect to efficiency of operation when running with a light load, i. e., with a shortened conveyor.

20 More particularly in the art of coal mining, it has been customary to construct special systems for different operations or conditions of operation. Such a practice has been objectionable not only due to the non-flexibility 25 of the system from an operating standpoint, but from the disadvantages with respect to power consumption averaged over the entire period of time during which the system is in use. With systems of special construction, 30 it has been necessary, according to prior practices, to provide a centralized drive capable of handling the maximum load imposed on the system. When the system has been considerably shortened, or when the load is at a 35 minimum, the conveyor is overpowered, thereby involving an unnecessary expenditure of energy. On the other hand, when operating under a full load, the strain on the entire length of conveyor by reason of the 40 centralized drive has been not only objectionable with respect to such units but has been a determining factor in limiting the length 45 thereof.

50 Attempts have heretofore been made to 55 overcome this difficulty by constructing special systems embodying a distributed drive, which driving means have been definitely and fixedly located whereby operating flexibility has not been possible. The objections before referred to with respect to power consump-

tion, flexibility and adaptability to a wide variety of uses and positions have also been inherent in constructions of this character.

The present invention has for one of its objects the provision of a conveying system of extremely flexible nature from an operating standpoint in that it is adapted to be lengthened or shortened at will by predetermined unit lengths, the system comprising a plurality of separable unit sections removable and replaceable at will, certain of the sections being adapted for substitution for and addition to other unit sections at will and comprising driving means preferably constituting a unitary part of such sections and movable therewith.

Another object of the present invention is to provide a conveyor system capable of almost universal use, and not only much lighter and more convenient to handle than systems heretofore employed but also having a possible range of operation not limited with respect to variations in load or in the length of the system.

With the above objects in view, our invention contemplates an improved sectional unit arrangement and construction, and a conveyor system formed of a plurality of such units arranged in series, end to end. The improved sectional unit preferably comprises a frame carrying an endless conveyor and, where desired, having permanently incorporated therein and bodily removable therewith, a suitable driving mechanism. The endless conveyor is of such nature that it is adapted to be disconnected and its separated ends reunited with similarly separated ends of the conveyor of another section when the frames of two such sections are aligned in series and secured in abutting relationship. To this end the conveyor preferably comprises reticulated pans or other load carrying elements, the joints between the pans or other elements being of such nature that the conveyor can be broken at any point for the purpose referred to, and the dimensions of the individual elements bearing a definite relation to the construction of the frame of each section.

It is further contemplated that sections of the general character referred to shall be connected to or disconnected from other sections to produce a continuous unbroken conveyor of any desired length, the power for driving the conveyor being furnished by one or more

driving units carried by the individual sections and located as required for the most effective operation of the conveyor. The driving means for the driving units may comprise 5 suitable driving shafts permanently incorporated in the frames of the driving units whereby they bear a definite relation to the conveyor or section of conveyor carried thereby, the shafts being extended and cooperating with a 10 suitable source of power such as an electric motor, the motors being connected by suitable wiring to a common source of electric energy, such as a central power station.

In the accompanying drawings there are 15 shown, for purposes of illustration only, certain preferred embodiments of the present invention, it being understood that the drawings do not define the limits thereof and that changes may be made in the construction and 20 operation disclosed without departing from the spirit of our invention or the scope of our broader claims.

In the drawings:—

Figure 1 is a longitudinal vertical sectional 25 view of a sectional unit constructed in accordance with our invention, the unit being illustrated as in operative relation to a portion of an adjacent unit;

Figure 2 is a vertical transverse sectional 30 view on the line II—II of Figure 1 looking in the direction of the arrows;

Figure 3 is a fragmentary plan view of the construction illustrated in Figure 1;

Figure 4 is a detail view in vertical longitudinal section showing an alternative construction of conveyor pan;

Figure 5 is a diagrammatic side elevational view illustrating another form of conveyor in accordance with the present invention;

Figure 6 is a perspective view of a portion 40 of the head section of the conveyor illustrated in Figure 5;

Figure 7 is a detail perspective view illustrating the construction of the load carrying 45 elements;

Figure 8 is a perspective view illustrating the construction and manner of assembly of the shafts and rollers for the conveyor;

Figure 9 is a diagrammatic top plan view 50 illustrating the cooperating relationship of a driving unit with an adjacent unit;

Figure 10 is a side elevational view of the construction illustrated in Figure 9;

Figure 11 is a vertical transverse sectional 55 view on the line XI—XI of Figure 10 looking in the direction of the arrows, and

Figure 12 is a vertical transverse sectional view on the line XII—XII of Figure 10 looking in the direction of the arrows.

In the embodiment of the invention illustrated in Figures 1 to 3 of the drawings, the frame for each of the unit sections may comprise transversely extending sleepers 1, longitudinal sills or girders 2, and vertical corner posts 3. A number of vertical posts 4 may

also be distributed along both sides of the frame intermediate its ends to give added strength and to provide a support for the driving and connecting elements hereinafter described.

Secured to the inner sides of the upper and lower girders 2, are rails or angle irons having a tread portion 5, and vertical retaining flanges 6. At the ends of the section the upper rails curve downwardly on a radius which 75 brings the ends 7 of the operating rail to a point spaced from and above the lower rails.

The conveyor is illustrated in these figures as made up of shallow metal pans with flat bottoms 8 and side walls 9. On the ends of the bottoms 8 there are formed fingers 10 which are bent around to constitute hinge knuckles on one pan cooperating with similar knuckles on an adjacent pan, the hinges being completed by pins 11 on the ends of which are 80 mounted carrying rollers 12. These rollers are adapted to travel on the tread portions of the tracks 5, above and below, and also on the curved end portions of said tracks. At the 85 lefthand end, the lower rail picks up the rollers 12 as they sag from the ends of the upper rail, and at the righthand end the rollers are raised from the lower rail and again drawn upwardly against the upper rail as indicated in dotted lines in Figure 1. The number and 90 length of the pans is so calculated that a given number thereof can be linked together to form an endless conveyor of the proper length for operation on the tracks of a single section; and the longitudinal dimensions of the frames are so calculated that, when the ends of two 95 frames are abutted, and the hinge between two pans adjacent the abutting end of one frame is broken by withdrawing the pin 11, the ends of the belt thus separated may be swung upwardly and outwardly as indicated in dotted lines in Figure 1 and coupled with the ends of the belt or conveyor carried by an adjoining section. It will be noted that in thus connecting the conveyors of adjoining sections, the 100 total length of the belt must be shortened by the omission of two pans from one or the other of the sections.

For driving the conveyor there is preferably provided driving means built in one or more of the sections and bodily removable therewith. This driving means preferably comprises a shaft 14 journaled at its ends in vertical frame posts 4 and carrying a sprocket 15. This driving means may be operated in any desired manner as by a motor 13 transmitting power thereto in any preferred way as by belts 16 and 17 and an intermediate step-up pulley 18. A second sprocket 19 may be similarly mounted on a 115 shaft 20 and driven from the sprocket 15 by an endless chain 21. At suitable intervals 120 this chain is provided with special links 22 having outwardly projecting lugs 23 adapted to engage projections 24 rigidly secured to 125

the bottoms of the pans 8. As shown, the lugs 23 engage the projections 24 both on the upper and lower runs of the conveyor, thus driving both the working and returning runs thereof. By this arrangement the driving connection with the conveyor is situated intermediate the ends of the frame and the driving lugs engage the driven projections at points which are relatively far apart as compared with driving connections of the prior art. This construction constitutes a valuable feature of our invention and plays an important part in enabling us to drive a conveyor comprising a plurality of sections at a plurality of distributed points. The reason for this is that the driving connections of the prior art, usually comprising a sprocket at one end of the frame meshing with the chain to which the conveyor elements are secured, cannot be conveniently adapted to drive the belt at intermediate points. Moreover, the driving connection of the present invention permits the employment of a simpler belt construction, the usual chain which forms one part of the driving connection in the conveyors of the prior art being entirely dispensed with.

It will be understood that a complete system in accordance with this embodiment of the invention may comprise any number of power units and any number of units not having driving means incorporated therewith, the units being assembled in any desired arrangement, the invention contemplate plating the insertion between power units of one or more sectional units substantially similar thereto but lacking the driving means.

In Figure 4 an alternative construction of the pan hinges is shown. In this modification, the projections 24 are not required, the hinge knuckles 10^a being formed with their axes wholly below the bottom of the pans and cooperating directly with the lugs 23.

In Figures 5 to 12 both inclusive there is illustrated a modified, and for many purposes a preferred, form of the invention. In accordance with this embodiment of our invention, the entire conveyor comprises a plurality of units including drive sections as before referred to, and idle sections assembled in end to end relationship. The idle sections may comprise tread sections, curved sections, head sections and tail sections, whereby sections for any required purpose are available. In Figure 5 of the drawings there is illustrated in spaced relationship, and more or less diagrammatically, one section of each of the types referred to, these sections being respectively from left to right of the figure the head section 25, the curved section 26, the drive section 27, the straight section 28 and the tail section 29.

Each of the sections comprises tracks 30 for the upper run of the conveyor and similar

tracks 31 for the lower run of the conveyor. These tracks may be in the form of angles of the general nature before referred to secured at their sides to vertically extending braces 32, certain of these braces being of U-shaped construction and providing transversely extending supporting portions 33. The braces 32 adjacent the ends of the respective sections may carry angles 34, one portion of which extends outwardly from the sides of the frames with one of the faces in substantial alignment with the ends of the frames. These outwardly projecting portions may be provided with openings 35, as illustrated in detail in Figure 12, adapted to receive fastening means 36 passed therethrough and provided with a key or other securing means 37 for holding the same in position. In this manner adjacent sections may be quickly connected or disconnected as required to permit the insertion or removal of sections, or the rearrangement thereof.

Each of the head sections is of special construction and includes a transversely extending shaft 38 carrying suitably shaped rolls 39 around which the conveyor is adapted to travel, while the tail sections comprise similar shafts 40 and rolls 41. If desired, the tail sections may also include adjusting means 42 for increasing or decreasing the tension on the conveyor by varying the distance between the centers of the respective shafts 38 and 40.

As clearly apparent from Figures 5, 9, 10 and 11, the drive section at a point intermediate its length has the tracks 30 and 31 relatively spread to accommodate a driving means in the form of a shaft 43 journaled in the frame of the drive section and carrying star wheel driving sprockets 44. The tread portions of the intermediate tracks 30 and 31 may be cut away to provide pockets 45 into which the sprockets may project. For driving the shafts of the drive sections, there may be provided suitable means such as motors 46 operatively connected to the shafts through clutches 47, gearing 48 and couplings 49. This driving arrangement, and particularly the driving shaft 43, constitutes a component part of each drive section whereby the same is bodily removable with the section. It will be understood that, if desired, however, the motor supporting frame per se may be detachably carried by the frame of the drive section, it being only essential that the driving means in the form of the shaft 43 and the sprockets 44 be actually built into the unit.

The conveyor may comprise a series of pans 50 having longitudinally extending straps 51 forming at their opposite ends hinge knuckles 52. The hinge knuckles on one pan co-operate with those of an adjacent pan to permit the reception of a combined pin and shaft 53. Each of these shafts is adapt-

ed to receive a roller 54 on each end, the rollers preferably being detachably secured in position by a washer 55 and a removable key 56, the keys cooperating with openings 57 in the ends of the shafts, as clearly apparent more particularly from Figure 8 of the drawings.

The rollers 54 are of such construction as to effectively cooperate with the tracks 30 10 and 31, and the tread portions thereof are of such width, as clearly shown in Figure 11, that a portion extends over the pockets 45 while another portion travels on the tracks adjacent these pockets. This permits the 15 star wheels 44 to directly engage the rollers 54 and thereby drive the conveyor. This obviates the necessity of providing special driving projections on the pans and at the same time provides a rolling contact between 20 the driving means and the conveyor whereby friction is reduced to a minimum.

It will be understood that any desired number of drive sections may be utilized in a single length, the drive sections cooperating 25 with any desired arrangement and number of intermediate sections either straight or curved. Thus, as the conveyor is lengthened, additional drive sections may be added at will to distribute the driving strain in the 30 most advantageous manner.

It will be further understood by those skilled in the art that the drive sections may or may not be of the same length as the other sections. In many cases, due to the additional weight of the built-in driving means, 35 it is desirable to have the drive sections relatively shorter to make the handling thereof correspondingly easier. In all cases, however, their length must bear a definite 40 relation to the length of the elements comprising the conveyor, to enable the desired insertion, substitution or addition of the drive sections.

The present application constitutes a continuation in part of our copending application, Serial No. 501,222, filed September 17, 45 1921.

The advantages of the present invention will be apparent from the foregoing to those skilled in the art. The arrangement permits 50 flexibility of operation by reason of the possibility of extending the conveyor to any desired length practically without limitation, the total power required to drive the conveyor of a given length being proportionately distributed to a plurality of driving means located at spaced points. This obviates the use of a power unit at any point 55 capable of driving a fully loaded conveyor 60 when extended to its maximum length and therefore necessarily considerably less convenient to shift from place to place than a similar power unit of the character herein contemplated, and also less efficient when operating under less than the maximum load. 65

A further advantage is inherent in the minimization of the strain on the conveyor and transmission elements operatively connecting the same with the driving means as compared to the strain where power is applied at a single point or at a plurality of fixed predetermined points with a distributed drive along the length of the conveyor with each drive located as required by the particular operating conditions encountered, a desirable operating efficiency is insured, strain is reduced and wide variation in load over varying distances is more effectively accomplished.

We claim:

1. A conveying system adapted to be lengthened or shortened at will by predetermined unit lengths, said system comprising a plurality of separable unit sections, an endless conveyor common to all of said sections, said sections being removable and replaceable at will with a corresponding length in the common conveyor, certain of said sections being adapted for substitution for and addition to other unit sections at will and having built-in driving means bodily movable therewith, said driving means providing a distributed drive for said common conveyor.

2. A conveying system adapted to be lengthened or shortened at will by predetermined unit lengths, said system comprising a plurality of separable unit sections, an endless conveyor common to all of said sections, said sections being removable and replaceable at will with a corresponding length in the common conveyor, certain of said sections being adapted for substitution for and addition to other unit sections at will and having built-in driving means bodily movable therewith, said driving means comprising a shaft extending transversely of said sections and journaled therein.

3. A conveying system adapted to be lengthened or shortened at will by predetermined unit lengths, said system comprising a plurality of separable unit sections, an endless conveyor common to all of said sections, said sections being removable and replaceable at will with a corresponding length in the common conveyor, certain of said sections being adapted for substitution for and addition to other unit sections at will and having built-in driving means bodily movable therewith, said driving means comprising a shaft extending transversely of said sections and journaled therein, there being motors positioned laterally of said sections for driving said shafts.

4. A conveying system adapted to be lengthened or shortened at will by predetermined unit lengths, said system comprising a plurality of separable unit sections including a head section, a curved section and straight sections all of which are removable and replaceable at will, at least one of said

straight sections having a built-in driving shaft bodily movable therewith, and an endless conveyor common to all of said sections.

5. A conveying system adapted to be lengthened or shortened at will by predetermined unit lengths, said system comprising a plurality of separable unit sections including a head section, a curved section, a straight section and a driving section all of which are removable and replaceable at will, said driving section having built-in driving means bodily movable therewith, and an endless conveyor common to all of said sections.

6. A conveying system adapted to be lengthened or shortened at will by predetermined unit lengths, said system comprising a plurality of separable unit sections including a head section, a curved section, a straight section and a driving section all of which are removable and replaceable at will, said driving section having built-in driving means bodily movable therewith, said driving means comprising a shaft extending transversely of the sections and journaled therein, 20 and an endless conveyor common to all of said sections.

7. A conveying system adapted to be lengthened or shortened at will by predetermined unit lengths, said system comprising a plurality of separable unit sections including a head section, a curved section, a straight section and a driving section all of which are removable and replaceable at will, said driving section having built-in driving means bodily movable therewith, said driving section and straight section being interchangeable at will, and an endless conveyor common to all of said sections.

8. A conveying system adapted to be lengthened or shortened at will by predetermined unit lengths, said system comprising a plurality of separable unit sections removable and replaceable at will, certain of said sections being adapted for substitution for and addition to other unit sections at will and having built-in driving means bodily movable therewith, and a common conveyor cooperating with said sections and with all of said driving means.

50 9. A conveying system adapted to be lengthened or shortened at will by predetermined unit lengths, said system comprising a plurality of separable unit sections removable and replaceable at will, certain of said sections being adapted for substitution for and addition to other unit sections at will and having built-in driving means bodily movable therewith, and a common conveyor cooperating with said sections and with all of said driving means, said conveyor comprising a plurality of pivotally connected unit-load carrying members.

60 10. A conveying system adapted to be lengthened or shortened at will by predetermined unit sections, said system comprising

a plurality of separable unit sections removable and replaceable at will, certain of said sections being adapted for substitution for and addition to other unit sections at will and having built-in driving means bodily movable therewith, tracks on each of said sections, and a common conveyor cooperating with the tracks on all of said sections.

5 11. A conveying system adapted to be lengthened or shortened at will by predetermined unit sections, said system comprising a plurality of separable unit sections removable and replaceable at will, certain of said sections being adapted for substitution for and addition to other unit sections at will and having built-in driving means bodily movable therewith, tracks on each of said sections, and a common conveyor cooperating with all of said tracks, said driving means cooperating with both runs of the conveyor.

15 12. A conveying system adapted to be lengthened or shortened at will by predetermined unit lengths, said system comprising a plurality of separable unit sections including a head section, a curved section, straight sections, a plurality of driving sections and a tail section all of which are removable and replaceable at will, said plurality of driving sections providing a plurality of distributed drives for said system, each of said driving sections being interchangeable at will with one of said straight sections, and having a built-in driving shaft bodily movable therewith, there being an endless conveyor common to all of said sections.

20 13. In a conveying system, a plurality of sections, a common extensible endless conveyor cooperating with all of said sections, any of said sections with a predetermined length of said common conveyor being removable or replaceable at will, and driving means constituting a part of certain of said sections, and removable therewith, said driving means being effective both on the working and returning runs of said conveyor, whereby a distributed drive at opposite parts of said conveyor and at any desired points throughout the length thereof may be established or destroyed at will by suitable substitution and positioning of the sections.

25 14. A conveying system adapted to be lengthened or shortened at will by predetermined unit lengths, said system comprising a plurality of separable unit sections including a head section, a curved section, and straight sections, all of which are removable and replaceable at will and a common conveyor cooperating with all of said sections adapted to be lengthened or shortened at will, a plurality of said straight sections being distributed throughout the system and having built-in driving shafts bodily movable therewith to provide a plurality of distributed drives for said system.

30 15. A conveyor system comprising in com-

bination, an endless conveyor adapted to be lengthened or shortened, and a supporting frame for said conveyor consisting of separable, bodily removable and replaceable sections, one or more of said sections having self-contained separately operated driving units in operative relation to said conveyor, said driving units being incorporated in the structure of their respective sections individually 10 when removed or for assisting similar sections when combined therewith.

16. A conveyor system according to claim 1, in which the driving units consist of separately energizable electric motors.

15 17. A conveying system adapted to be lengthened or shortened at will by predetermined unit lengths, said system comprising a plurality of separable unit sections removable and replaceable at will, certain of said 20 sections being adapted for substitution for and addition to other unit sections at will and having built in driving means bodily movable

therewith, and an endless conveyor common to several of said sections.

18. In a conveyor system, a plurality of sections, a common extensible endless conveyor cooperating with all of said sections, any of said sections with a predetermined length of conveyor being removable or replaceable at will, and driving means constituting a part of certain of said sections and removable therewith, said driving means being effective both on the working and returning runs of said conveyor whereby a distributed drive at opposite parts of the conveyor and at any desired points throughout the length thereof may be established or destroyed at will by suitable substitution and positioning of said sections.

In testimony whereof we have hereunto set 40
our hands.

WALTER D. STOCKLY.
EVERETT DRENNEN.
